197,570

COMBINED TOY TOP AND LAUNCHER

Vincent L. Endris, 336 Grandview, Glen Ellyn, Ill.

Filed Sept. 18, 1963, Ser. No. 76,625

Term of patent 14 years

(Cl. D34—15)

FIG. 1 is a side elevational view of a combined toy top and launcher showing my new design;

FIG. 2 is a top plan view;

FIG. 3 is a bottom plan view;

FIG. 4 is a rear end view; and

FIG. 5 is a front end view.

I claim:

The ornamental design for a combined toy top and launcher, substantially as shown.
